US0D1108888S

(12) **United States Design Patent** (10) **Patent No.:** **US D1,108,888 S**
(45) **Date of Patent:** ** **Jan. 13, 2026**

(54) **CONTAINER**

(71) Applicant: **Runway Blue, LLC**, Lehi, UT (US)

(72) Inventors: **David O. Meyers**, Layton, UT (US);
John R. Omdahl, II, Lindon, UT (US);
Paul James Faerber, Orem, UT (US)

(73) Assignee: **Runway Blue, LLC**, Lehi, UT (US)

(**) Term: **15 Years**

(21) Appl. No.: **29/930,276**

(22) Filed: **Feb. 28, 2024**

(51) **LOC (15) Cl.** **07-01**

(52) **U.S. Cl.**
USPC **D7/511**

(57) **CLAIM**

The ornamental design for a container as shown and described.

DESCRIPTION

FIG. 1 is a top isometric view of a container showing the claimed design;

FIG. 2 is a bottom isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top isometric view of another embodiment of the container

FIG. 10 is a bottom isometric view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

(Continued)

The broken lines in the figures show portions of the container that form no part of the claimed design.
